UNITED STATES PATENT OFFICE.

ADOLF WEIGNER, OF VIENNA, AUSTRIA-HUNGARY.

APPLIANCE FOR PRODUCING CASE-SHOT-LIKE ACTION OF EXPLOSIVE PROJECTILES.

SPECIFICATION forming part of Letters Patent No. 608,941, dated August 9, 1898.

Application filed November 6, 1897. Serial No. 657,695. (No model.)

To all whom it may concern:

Be it known that I, ADOLF WEIGNER, a subject of the Emperor of Austria-Hungary, residing at Vienna, in the Province of Lower Austria, in the Empire of Austria-Hungary, have invented certain new and useful Improvements in Appliances for Ordnance for Producing a Case-Shot-Like Action of Explosive Projectiles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

According to my invention, in order to enable explosive projectiles, whether grenade-shells, shrapnel, or case-shot, and whether provided with percussive fuse or double fuse, to be fired from guns so as to explode with case-shot-like action immediately on leaving the bore, I arrange a small resisting body either immediately in front of or just within the muzzle of the gun, so that, on firing, the projectile in striking against the said body is as once caused to explode. The resistance of the body must not exceed a certain limit, as otherwise damage might be done to the muzzle of the gun.

By the above-described means an already-loaded gun, the fuse of whose projectile may have been set to effect the explosion after a certain time, may be made to act with immediate case-shot action at the moment of an engagement when it may be necessary to repel an attacking enemy at close quarters, this being effected without changing the projectile. The case-shot action of the grenade will of course not reach as far as that of the shrapnel-shell; but up to a distance of two hundred paces it is quite sufficient. The further advantage is also obtained that every shrapnel with double igniter-fuse can be made to act as "zero" shrapnel without requiring to arrange the fuse specially for this function and without causing any complication in the equipment and use of the shrapnel. The arrangement of the said device for

causing the explosion of the projectile can be carried out in various ways. For the action it is immaterial whether it be more or less firmly attached to the gun, provided the action is not prejudicially affected thereby.

Experiments have shown that an iron plate weighing 0.1 kilo suspended by a thread close in front of the gun's muzzle suffices to bring into action the percussion-fuse employed for the Austrian nine-centimeter grenade. For the more sensitive double fuse of the shrapnel model 91 the certainty of action is still greater. On account of the destructive action of the fired projectile upon the said plate it is advantageous to arrange its connection with the gun in such manner that the latter, after delivering the shot, is at once ready for the reception of another similar body. By this means on the one hand the gun is preserved from unintended changes, and on the other hand it is possible to rapidly repeat the firing of case-shot, as may be required by the urgency of the moment of engagement.

On the accompanying drawings is shown, by way of example, a construction of the said device that can be operated by a single manipulation.

Figures 1, 2, and 3 show in sectional side view, front view, and plan the muzzle end of a gun with the device suspended close in front of the muzzle. Fig. 4 shows the device separately in front and side views.

The device here consists of a small plate *p* of any suitable resisting material, which is secured to a small plate *h*, of a less-resisting material, having two lateral projections. In order to enable this plate to be rapidly hung close in front of the muzzle, the top of the latter is formed with a recess *m*, in which is fixed a hook-shaped loop *o*, in which are hung the projections of the plate *h*. The plate *p* is destroyed on firing, and the gun is at once ready for the reception of another similar device.

I claim—

1. The combination with a gun, of a body suspended in front of its muzzle and adapted to be moved out of the path of and simultaneously therewith explode a projectile fired

from said gun by the impact of said projectile with said body, substantially as and for the purpose set forth.

2. The combination with a gun, of a tapering plate of less width than the bore of the gun and adapted to be suspended in front of the muzzle in the plane of the axis of its bore, said plate sufficiently heavy to explode a pro-

jectile striking it on leaving the gun, for the purpose set forth.

In testimony whereof I affix my signature in presence of two witnesses.

ADOLF WEIGNER.
